UNITED STATES PATENT OFFICE

156,468

UTILITY BOX

Bernard Ulvad, Leominster, Mass., assignor, by mesne assignments, to Foster Grant Co., Inc.,
Leominster, Mass., a corporation of Massachussets

Application July 8, 1948, Serial No. 147,425

Term of patent 14 years

(Cl. D58—11)

To all whom it may concern:

Be it known that I, Bernard Ulvad, a citizen of the United States, residing at Leominster, in the county of Worcester, State of Massachusetts, have invented a new, original, and ornamental Design for a Utility Box, of which the following is a specification, reference being had to the accompanying drawing, forming part thereof, in which:

Figure 1 is a side elevational view of a utility box, showing my new design;

Fig. 2 is a top plan view thereof, and

Fig. 3 is a bottom plan view thereof.

I claim:

The ornamental design for a utility box, substantially as shown.

BERNARD ULVAD.
